UNITED STATES PATENT OFFICE.

BENJAMIN J. ABBOTT, OF CHICAGO, ILLINOIS.

MACHINE FOR DRESSING CAR-WHEELS.

SPECIFICATION forming part of Letters Patent No. 443,928, dated December 30, 1890.

Application filed June 12, 1890. Serial No. 355,162. (No model.)

To all whom it may concern:

Be it known that I, BENJAMIN J. ABBOTT, a citizen of the United States, and a resident of Chicago, in the county of Cook and State 5 of Illinois, have invented new and useful Improvements in Machines for Dressing Metals, of which the following is a specification, reference being had to the annexed drawings, illustrating the invention, in which—

10 Figure 1 is a side elevation of a car-wheel and dressing-disk, the apparatus by which the car-wheel is heated before the application of the dressing-disk, and the apparatus for subjecting the car-wheel to cold water 15 and the dressing-disk to cold air and forming an upward current for the escape of heat from the surfaces in contact; Fig. 2, a section of the housing of the disk on line *x*; Fig. 3, a horizontal section on line *y*.

20 This invention relates to means in machines where a smooth metal surface is made to dress another metal surface for heating the metal to be dressed before applying the dressing-disk and in means for keeping the surfaces in contact from having too high a temperature.

The special machine to which this improvement is more particularly adapted is the one for dressing car-wheels in which the dressing-disk runs at a high rate of speed and the car-wheel at a much lower rate. In such work it is found that little or no progress can be made in dressing the car-wheel till it becomes quite warm. Therefore, to save the 35 cost of running the disk against the car-wheel to warm it, I provide means for heating it by a flame or other suitable means before the disk is applied to it. It is also found that both the car-wheel and disk become

40 overheated before one wheel can be dressed. To remedy this I provide means for putting a blast of cold air onto the disk and cold water on the car-wheel. I also provide means for conducting off the heat in a great measure during the dressing process, as the whole 45 is hereinafter fully described and shown.

A is a side elevation of an ordinary car-wheel to be dressed, the axle of which is shown at *A'* and is supposed to be rotated 50 by the usual well-known means.

The dressing-disk in side elevation is shown

at B, and its shaft *B'* is supposed to be connected with pulleys and belts, whereby a proper velocity is imparted. Over the car-wheel is placed a heating-chamber T, which 55 is lined with fire-brick or other material known to withstand fire. From this chamber a flue J leads up through the roof W of the inclosure in which the machine is set, and the lower portion of the flue extends through 60 a guide Y, that it may be elevated to permit a car-wheel to be placed under the heating-chamber or removed therefrom. Cords, weights *e*, pulleys *f*, and balancing-weights hold the heating-chamber and its attached 65 flue in any desired position to which they are moved. A cold-blast chamber E is made to project over the upper portion of the disk B, and it is provided with a flue *a*, which also projects through the roof W. 70

D R S is an oil-heater, which projects a flame *s* upon the car-wheel within the chamber T.

F represents an ordinary air force-pump, which by means of a pipe H puts air into a 75 receiver G. A pipe M M M conducts the air through a cooler L and into the chamber E to cool the disk B. A pipe I I I communicates with the receiver G and a vertical pipe K, and the latter pipe communicates with a 80 horizontal pipe X, which extends into both flues Q and J, and by means of extension-pipes O P upward currents are formed in said flues by the upward thrust of air. A pipe K communicates with the pipe X and pipe R, 85 whereby a blast is given to the flame *s*. A vessel C, containing cold water, is placed below the wheel A for the water to cool the wheel.

The operation is as follows: To place the 90 car-wheel in position, lower the vessel C by means of the set-screw U, which secures its standard to the foundation V, and raise the heating-chamber T. Then leave the vessel C down and lower the heating-chamber to the 95 position shown and shut the cocks *a c*. Start the heater D R S and open cock *d*. When the wheel A is sufficiently heated, put the disk to work, and so soon as it and the wheel A become too hot put out the heater. Let the 100 cold air in by pipe M M M and the air into pipes O P, whereby the heated air may es-

cape and the cold air have its effect on the disk. Also elevate the vessel C to bring cold water to the wheel A.

Having thus described my invention, I 5 claim and desire to secure by Letters Patent of the United States—

1. In a machine for dressing metal, an improvement for heating the metal to be dressed, consisting of an adjustable heating-chamber 10 and an upwardly-projecting flue as a part thereof, a suitable heating device projecting a flame into the compartment, and an air-blast to force the flame onto that portion of the wheel within the chamber, as specified.
- 15 2. In a machine for dressing metal, an improvement for cooling the disk, consisting of

a hood covering the upper portion of the same and the hood provided with a flue, in combination with an air-pump, an air-receiver, an air-cooling chamber, and pipes for conducting the cold-air blast into that portion of the disk within the hood, as specified.

3. In combination with an air-pump, cooling-chamber, and pipes for putting a cold blast onto the disk, an adjustable vessel to 20 contain a cold fluid placed below the wheel 25 to be dressed, substantially as specified.

BENJAMIN J. ABBOTT.
